UNITED STATES PATENT OFFICE.

JOHN W. WHITEHEAD, OF CHICAGO, ILLINOIS.

THEATRICAL RUNWAY.

1,255,256.

Specification of Letters Patent.

Patented Feb. 5, 1918.

Application filed June 15, 1917. Serial No. 175,046.

To all whom it may concern:

Be it known that I, JOHN W. WHITEHEAD, a citizen of the United States, and resident of Chicago, in the county of Cook and State 5 of Illinois, have invented certain new and useful Improvements in Theatrical Runways; and I do hereby declare that the following is a full, clear, and exact description thereof.

- 10 My invention relates to certain new and useful improvements in theatrical run-ways, of that type in which the run-way extends outwardly from the stage and over the alining row of seats.
- 15 The primary object of this invention is to provide such a device which will be capable of adjustment to permit usage thereof with floors having varying degrees of inclination.
- 20 Another object resides in the provision of such a theatrical run-way which will be portable in order to permit the ready removal thereof from place to place.

25 A further object resides in the provision of such a knock down run-way having means by which varying lighting effects may be obtained.

With the above and other objects in view, which will appear as the description proceeds, my invention resides in the novel construction, combination and arrangement of parts substantially as hereinafter described and claimed, it being understood that such changes in the precise embodiment of my invention may be made as come within the 30 scope of the claims.

In the accompanying drawings I have illustrated one complete example of the physical embodiment of my invention constructed according to the best mode I have so far devised for the practical application of the principles thereof, in which:

Figure 1 is a side elevational view of a theatrical run-way showing the same assembled, with parts in section in order to disclose details of construction, and

Fig. 2 is a sectional view in perspective taken on the line indicated by line 2—2 of Fig. 1.

Referring now more particularly to the accompanying drawings, in which the stage and seats are shown in conventional outline and designated by the numerals 5 and 6 respectively, it will be seen that my novel 50 run-way is adapted to be extended from the forward part of the stage and comprises a

series of vertical supporting members 7 arranged in parallel relation, and having braces 8 connecting the transversely alined supports and sills 9 connecting the longitudinally alined supports.

As it will be readily seen by reference to Fig. 2, the sills 9 have their inner edges recessed as at 10 for supporting the glass or other transparent floor 11, which together 60 with the top face of sills 9 forms the platform of the run-way. The floor 11 is cushioned in this recess by means of a rubber or felt strip 12, and is held in place by a metal strip 13 secured to sills 9 by suitable wing 65 nuts 14 and having its sides secured to the inner edges of the sills 9 is a trough 15 in which are disposed a series of electric lamps 16 for illuminating the platform.

Running along the outer edges of the sills 75 9 are guards 17 from which extend curtains 18 for hiding the row of seats 6 and for giving the run-way a more attractive appearance. At the forward end of the run-way is disposed an arch 19 formed of any 80 suitable electric conduit and to the top thereof is secured a conduit 20 which extends centrally above the run-way and has its rear end secured to a supporting post 21, and intermediate the ends of the conduit 85 20 are a series of electric lamps 22 having suitable deflectors 23 for throwing the light downwardly upon the run-way.

The several sections completing this run-way are secured together by means of any 90 suitable pins, nails or screws 24, which are such as to permit the ready removal of any or all of the several sections forming this run-way. The lowermost portions of the support 7 engage extensions 25 which permit the ready adjustment therein of said supports in order to accommodate the run-ways to floors of varying degree of inclination.

It is my purpose to arrange variously colored lights in the trough 15 in order that various lighting effects may be had and as the specific means for procuring this constitutes no important part of my invention the same has not been shown in the drawing. 105

I claim:—

1. A theatrical device of the class described comprising a run-way adapted to extend outwardly of a stage, said run-way including a transparent bottom portion, and 110 means for illuminating said bottom portion.

2. A theatrical device of the class de-

scribed comprising a run-way adapted to extend outwardly of a stage, said run-way including a transparent bottom portion, illuminating means beneath the bottom portion, and reflecting means for throwing the light from said illuminating means through the transparent bottom portion.

3. A portable run-way of the class described comprising a series of alined vertical supports arranged in paired relation and having transverse bracing means, sill extension members secured to the lower ends of the support for permitting adjustment of the height thereof, said sill members connecting the longitudinally alined supports and having their inner edges grooved, and a floor portion fitting in said grooves and forming with said sills the platform of the run-way.
- 10 4. A portable run-way of the class described, comprising adjustable vertical supports, a platform mounted upon the supports having its central portion transparent, means disposed beneath the said transparent portion for illuminating the run-way, and means disposed above the run-way for providing further illumination for the run-way.
- 15 5. A portable run-way of the class described comprising a series of vertical sup-

ports arranged in paired relation and having transverse bracing means, sill extension members secured to the lower ends of the supports for permitting adjustment of the height thereof, said sill members connecting the longitudinally alined supports and having their inner edges grooved, a transparent floor portion fitting in said grooves, and forming with said sills the platform of the run-way, and means disposed beneath the transparent portion for illuminating the run-way.

30 6. A portable run-way of the class described comprising a series of vertical supports arranged in paired relation and having transverse bracing means, and sill extension members secured to the lower ends of the supports for permitting adjustment of the height thereof, said sill members connecting the longitudinally alined supports and having their inner edges grooved, a 35 transparent floor portion fitting in said grooves, a trough disposed beneath the transparent portion, and lights in said trough.

35 In testimony that I claim the foregoing I have hereunto set my hand at Chicago, in the county of Cook and State of Illinois.

40 JOHN W. WHITEHEAD.
